UNITED STATES PATENT OFFICE.

WILBER D. FORSYTH AND ENOS T. BELL, OF PITTSBURG, PENNSYLVANIA,
ASSIGNORS TO THE UNION BOILER TUBE CLEANER COMPANY, OF SAME
PLACE.

MACHINE FOR OPERATING BOILER-TUBE CLEANERS.

SPECIFICATION forming part of Letters Patent No. 637,774, dated November 28, 1899.

Application filed December 4, 1897. Serial No. 660,753. (No model.)

To all whom it may concern:

Be it known that we, WILBER D. FORSYTH and ENOS T. BELL, citizens of the United States, and residents of Pittsburg, in the county of Allegheny and State of Pennsylvania, have invented certain new and useful Improvements in Machines for Operating Boiler-Tube Cleaners; and we do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a side elevation, partly broken away and illustrating the invention applied to a boiler as in use. Fig. 2 is a plan view of the gear-head and connections. Fig. 3 is a sectional view of the same. Fig. 4 is a cross-section of a boiler-drum, showing the manner of supporting the appliance. Figs. 5, 6, and 7 are detail views. Fig. 8 is a detail view of the universal-joint connection between the driving-shaft within the drum and its driving-shaft. Fig. 9 is a detail view of the clutch which controls the operation of the counter-shaft.

This invention has relation to mechanism for the purpose of operating boiler-tube-cleaning devices while the latter are being fed through tubes which are more or less curved, as in some types of water-tube boilers, and the invention is designed to provide practical and efficient mechanism for this purpose.

With this object in view the invention consists in the novel construction and combination of parts, all as hereinafter described, and pointed out in the appended claims.

In the accompanying drawings, in which we have shown our invention as in use in connection with a boiler of the Stirling type, the letter A designates the drum of the boiler, and B the water-tubes thereof.

C designates a guide-shaft formed with a keyway c, running throughout its length and supported firmly in its position in the upper portion of the boiler-drum, longitudinally thereof. The supports for this shaft consist

of plates D of the form best shown in Fig. 4 and which are securely bolted to triangles or standards E. These triangles or standards are temporarily set up within the drum, one at each end thereof, and are preferably constructed with turnbuckles E' in order that they may be readily adjusted and firmly screwed up to place. Mounted to slide longitudinally upon the said guide-shaft is a gear-head which has an extended sleeve F, formed with a spline or feather f, which engages the keyway c of the shaft, thus holding said head in proper position, while permitting it to be moved freely back and forth on said shaft throughout its length. Projecting from the said sleeve are arms F', which are provided with bearings for a driving-shaft G, which is parallel with the guide-shaft and whose end portions have bearings in the plates D. Said shaft G has therein a keyway g and is further supported and held against vibration by means of one or more sliding plates or brackets H, which have feathers which engage the keyway of the guide-shaft. Journaled in the said gear-head is a short shaft I, which carries two miter gear-wheels I' and I". On the shaft G and engaging its keyway is a similar gear-wheel J, whose teeth engage the teeth of the gear-wheel I'. Pivoted on the said shaft I is a yoke K, which is adapted to be swung in a plane parallel with the guide and driving shafts. Mounted in said yoke upon an axle L is a miter gear-wheel L', which meshes with the gear-wheel I". Connected to the shaft L is a flexible shaft M, to which is attached the tube-cleaning device or head W, which is shown as being of the sectional jointed construction described and claimed in our pending application, Serial No. 660,752. This flexible shaft is provided with an intermediate support and bearing consisting of a number of pulleys N, which are carried by an arm N', attached to a standard N", set up within the drum A and provided with a turnbuckle n for its adjustment.

O is a sprocket-chain whose ends are made fast to the gear-head and which at the distant end of the drum passes over a small sprocket-wheel O', which is adjustably mounted in a

slotted arm O'', secured to the adjacent plate D. Connected to the plate D at the opposite end of the drum is an arm or frame P, which carries at its upper portion two sprocket-wheels P' P'' and at its lower end portion a third sprocket-wheel P''', which is provided with an operating-crank p. The two branches of the chain pass, respectively, over the wheels P' P'', and thence down and around the wheel P'''. By the operation of the crank p the head may be moved in both directions to any desired position on the guide and driving shafts.

In the arrangement illustrated the driving-shaft is extended out through a small opening in the head of the drum and is connected with a short shaft R by means of a universal joint S'. Said short shaft is journaled in a block S on a vertical standard S'', or it may be in any other suitable manner. On said shaft R is a pulley T, which is driven by a belt T' from a counter-shaft T''. Said counter-shaft has a clutch U, from which a shipper-rope U' is carried into the drum A, through the manhole thereof, so that the operator inside of the drum can put on or cut off the power, as may be necessary.

In setting up the device the drum-head must be drilled to provide the opening for the driving-shaft to pass through, and this opening should be tapped to receive a plug for the purpose of closing it after the operation is completed. During the operation a bushing V is placed in said opening to prevent injury to the thread.

The manner of using the device will be understood from the foregoing and from the accompanying drawings without detailed description thereof. To clean the tubes at the left-hand end portion of the boiler, the yoke K is reversed on the shaft I from the position in which it is shown in Fig. 1 and the gear-head is moved toward the right-hand end.

In case it should not be desired to drill the head of the drum for the driving-shaft G said shaft can readily be driven by suitable gear connections through the manhole of the drum.

Having thus described our invention, what we claim as new, and desire to secure by Letters Patent, is—

1. In mechanism for the purpose described, the combination of supporting devices adapted to be set up within the drum of the boiler to be cleaned, a guide-shaft supported thereby, a parallel driving-shaft, means for driving the same, the gear-head slidably mounted upon the said shafts and having gearing which is actuated by the said driving-shaft, and a tool-operating shaft connected to the gearing of said head, substantially as specified.

2. In mechanism of the class described, the combination of supporting devices adapted to be set up within the drum of the boiler to be cleaned, a guide-shaft supported thereby, a parallel driving-shaft, means for actuating

the same, a gear-head slidably mounted upon the said shafts and having gearing which is actuated by the driving-shaft, a flexible tool-operating shaft connected with the gearing on said head, and means for causing the end-wise travel of the gear-head upon said guide and driving shafts, substantially as specified. 70

3. In mechanism of the class described, the combination of supporting devices adapted to be set up within the drum of the boiler to be cleaned, a guide-shaft supported thereby, a parallel driving-shaft, means for actuating the same, a gear-head slidably mounted upon 80 the said shafts and having gearing which is actuated by the driving-shaft, a tool-operating shaft connected with said gearing, and a sprocket-chain connected at its ends to the said gear-head, intermediate bearings for 85 said chain, and means for operating the same to thereby move the said head in either direction, substantially as specified.

4. In mechanism of the character described, the combination of the supporting devices, 90 the parallel guide and driving shafts, the gear-head mounted to slide on said shafts and carrying gearing which is driven by the said driving-shaft, means for actuating said driving-shaft, the cleaner-head, the flexible shaft 95 carrying and operating the same and driven by the gearing of said head, and intermediate supports and bearings for the said flexible shaft, substantially as specified.

5. In mechanism of the class described, the combination with supports adapted to be set up within the drum of a boiler, guide and driving shafts supported thereby, a gear-head slidably mounted on said shafts, a short shaft journaled in the said head, and geared 100 to the said driving-shaft, a yoke pivoted on said short shaft, a gear-wheel carried by said yoke and engaging a gear-wheel on the short shaft, and a flexible tool carrying and operating shaft connected to the gear-wheel on 105 the yoke, together with means for actuating said driving-shaft, substantially as specified.

6. In mechanism of the class described, a power-driven shaft, bracket or supporting devices adapted to be set up within the drum of 115 a boiler to support said shaft with relation to the series of tubes to be cleaned, a flexible shaft operatively connected to the first-named shaft exteriorly of the said tubes, and arranged to be carried to any one of said tubes 120 without changing the position of the first-named shaft, and a tube-cleaning tool or head carried by said flexible shaft, substantially as specified.

7. In mechanism of the class described, the combination with the guide and driving shafts and the gear-head carried thereby, of the standards or triangles which support the said shafts, a slotted arm carried by one of these supports, an arm or frame carried by the other support, a sprocket-wheel mounted in said slotted arm, other sprocket-wheels mounted on the said arm or frame, one of which wheels has an operating-crank, and a sprocket-chain 130

whose ends are connected to opposite sides of the said gear-head and which is carried by the said sprocket-wheels, substantially as specified.

5 8. In mechanism of the class described, the combination with the guide and driving shafts, the gear-head, means whereby said gear-head may be moved along the said shafts, and the gearing in said head connected to and
10 driven by the said driving-shaft, of a flexible tool-operating shaft operatively connected with the gearing of said gear-head, an adjustable standard, and a number of pulleys carried thereby and forming an intermediate
15 support or bearing for the said shaft, substantially as specified.

9. In mechanism of the class described, the combination of supporting devices adapted to be set up within the drum of a boiler, a
20 driving-shaft supported thereby, and extended through the drum-head of the boiler, and having a universal joint exteriorly of the boiler, driving mechanism for said shaft, and means whereby the operation of such mechanism may be controlled at will, together with
25 a flexible tool-carrying shaft geared to said

driving-shaft within the said drum, substantially as specified.

10. In mechanism of the class described, the combination with supporting devices adapted to be set up within the drum of a boiler, of a flexible tool-carrying shaft supported thereby, a jointed tube-cleaning tool carried by the said shaft and gearing supported by the said supporting devices and adapted to be connected to driving mechanism exterior to the said drum, substantially as specified. 30

11. In mechanism for operating a tube-cleaning tool, supporting-heads having upper bearing-faces, a longitudinal connecting-bar 40 and extensible diverging legs connected with lateral lugs in the heads and adapted to bear against the boiler-drum and to clamp the heads in position, substantially as set forth.

In testimony whereof we affix our signatures in presence of two witnesses. 45
